APPARATUS FOR PROCESSING COAL

Andrew F. Howe, University City, Mo., assignor
to B H & M Company, St. Louis, Mo., a corpora-
tion of Missouri

Application June 5, 1939, Serial No. 277,428

4 Claims. (Cl. 233—21)

This invention relates to apparatus for processing coal; and has special reference to an apparatus for reclaiming usable coal from sludge and from slurry that have heretofore usually been discarded as waste materials, with consequent loss to operators and dealers.

An object of the invention is to provide an apparatus for processing waste coal sludge and slurry in a manner to assort and separate into one mass the materials, including the usable coal, to be subsequently processed to remove and separate the usable coal from the waste materials and finer particles that will remain suspended in water during the subsequent processing, and to provide means for satisfactorily effecting the final separation of the usable coal from the floating waste materials.

Another object of the invention is to provide an apparatus including means for effectively and satisfactorily controlling the amount of sludge and slurry passing from one part of the apparatus to another in order to prevent the centrifuge device, included in the apparatus and which effects the final step in the separation process, from becoming overloaded, and for delivering to said centrifuge device the proper amount of materials to obtain best and most satisfactory results.

Another object of the invention is to provide a solution of the problem of separating and processing to a usable condition coal that has heretofore been discarded as waste material along with other waste materials such as slate, earth, stone, and other non-combustible elements.

Various other objects and advantages of the invention, which has been satisfactorily used for the attainment of the desired effects and results herein suggested or otherwise known, will be made apparent from the following description, reference being made to the annexed drawing, which is a side elevation with some of the parts in section of one embodiment of the apparatus.

In the arrangement of the apparatus shown the coal sludge or slurry in a highly fluent state is discharged from a conduit 1 onto the upper end of an inclined vibratory screen 2 having a mesh of proper size for the purposes desired. The size of the screen required to attain best results in different instances may be determined empirically so that most of the water and usable coal will pass through the screen while the oversize solid fragments are discharged from the screen into an inclined chute 3 leading to a place of disposal. As stated, the screen 2 is vibrated when in use, and such movements may be im-

parted to the screen by any devices ordinarily used for such purposes. The screen is mounted on pivoted supports 4 which permit free vibratory movements thereof. The supports 4 are mounted on the frame 5.

A tank 6 adapted to receive the sludge and slurry containing the usable coal that pass through the screen 2 is supported by the frame 5 below said screen and is open at the top. The bottom of the tank 6 is formed with an outlet opening 7 controlled by a valve 8. The valve 8 is attached to a stem 9 mounted for vertical sliding movements in a guide 10 and having its lower end pivoted to an operating lever 11 operatively mounted on a support 12. A spring 13 may be connected with the guide 10 and the lever 11 between the stem 9 and the support 12 in order to actuate the lever 11 in a direction to move the valve 8 to closed position in the opening 7.

A rotary shaft 14 extends transversely through the lower portion of the tank 6 above the bottom thereof and supports an eccentric 15 outside of the tank which is engaged by a ring formation 16 on the upper end of a link 17 having its lower end pivoted to the lever 11. A clutch portion 18 on the eccentric 15 may be engaged and disengaged by a clutch 19 splined for sliding movements on the shaft 14 into and out of clutching engagement with the clutch portion 18 in order to rotate the eccentric 15 by the shaft 14 or leave the shaft 14 free to rotate without rotating said eccentric, as desired. A lever 20 engages the clutch member 19 and is operative to move said clutch into and out of engagement with the clutch portion 18. When the clutch member 19 is in engagement with the clutch portion 18, the eccentric 15 operates the link 17 and thereby the lever 11 to open and to close the valve 8 intermittently during rotation of the shaft 14; and, when the clutch is disengaged, the shaft 14 may continue to rotate without operating the valve 8, leaving said valve entirely closed or entirely open, or in an intermediate position. The shaft 14 may be rotated continuously when the apparatus is in use by driving connections 21. The shaft 14 extends across the inside of the tank 6 above the bottom thereof and above the valve 8, and has a number of agitator arms 22 attached thereto so that, when the apparatus is in use and the shaft 14 is rotating, the sludge or slurry within the tank 6 is constantly agitated to maintain the entire contents of the tank in a fluent state.

The contents of the tank 6 rises to the level 23, and a portion of the contents flows from the

tank through an outlet pipe 24 opening into the upper end of a clarifier mechanism 25. The agitator device 22 prevents settling of the lighter particles included in the fluent sludge and slurry, causing said particles to rise to the top and to be carried out with a part of the water into and through the pipe conduit 24 and thence to the clarifier 25. In this way, the mechanism associated with the tank 6 functions to remove a considerable portion of the undesired or non-useful particles that had passed through the screen 2 and to separate them from the remaining sludge and slurry which passes from the tank 6 through the opening 7 into a tank 26.

The stem 9 extends through one wall of the tank 26 and the valve 8 operates within the upper portion of said tank. The tank 26 constitutes a conduit device to receive the sludge or slurry from the tank 6 and to discharge the same into the upper end of a centrifugal machine enclosed within a housing 27. One wall of the tank 26 may be formed with louver devices 28 through which the sludge or slurry passing through the tank 26 may be observed to determine the character and quality thereof.

The centrifugal machine enclosed within the housing 27 comprises a rotary inner cone 29 rotated at high speed by driving connections 30 the specific form of which constitutes no part of the invention claimed herein. The conduit 31 opens from the bottom of the tank 26 and extends downwardly through the top of the centrifuge housing 27 and discharges the sludge or slurry onto the inner cone 29. A series of spiral flights 32 are attached to the outer side of the cone 29 and are operated thereby within the conical space 33 provided between the screen 34 and the cone 29 and attached to the inner side of the conical screen basket 35 having numerous outlet slots 36 therein. The slots 33 extend circumferentially and are in staggered relationship so that a screen basket is formed which supports the additional screen 34. The screen basket 35 and the attached screen 34 are both rotated by the mechanism 30 in a manner and by devices not specifically shown. The centrifugal force produced by the rapid rotation of the inner cone and the flights 32 attached thereto effects a separation of the usable coal from the refuse and most of the water because the refuse and most of the water are discharged through the screen 34 and screen basket 35 into a space 37 formed between said screen basket 35 and the centrifuge housing 27. The usable coal is discharged downwardly from the space 33 onto a conical apron 38 and thence into a chute 39. The apron 38 is rotated by the mechanism 30 and includes a number of flights 40 which sweep the coal into the chute 39 from which the coal 41 is discharged onto an appropriate conveyor 42.

By this apparatus operated in this manner, the larger fragments of coal and waste material are first separated by the screen 2 from the usable coal that may pass through said screen. The sludge or slurry discharged through the screen 2 into the tank 6 may be constantly agitated by the agitator devices 14 and the suspended lighter particles caused to flow out through the conduit 24 while the usable coal having a maximum size passes through the opening 7 into the conduit tank 26 and thence through the conduit 31 into the centrifugal machine. All of the operating mechanisms may be operated from a single source of power or not, as desired. When once placed

in operation, the apparatus will continue to operate indefinitely and to discharge coal 41 satisfactorily processed and separated from refuse that had previously been considered and discarded as waste.

The water and suspended materials passing to the clarifier 25 are separated so that the larger particles of suspended materials are discharged through an outlet 43 and the water through a conduit 44 leading to a reclaimer tank (not shown) whereby the water may be reclaimed for repeated use.

By use of this apparatus, the force of gravity affecting the finer mesh impurities that pass through the vibratory screen 2 is increased or stepped up several hundreds of times. These finer mesh impurities are thrown through the perforated screen 34 and are discharged as waste with the effluent through the outlet pipe 66 leading to the clarifier mechanism 25. A supply of fresh water may be admitted into the tank 6 through a valve controlled pipe 67, thereby replacing the effluent that passes out through the outlet pipe 24. The pipe 67 opens preferably into the bottom of the tank 6 so that the inflowing water cooperates with the agitator 14 to maintain the sludge and slurry in proper condition for further processing, and to prevent settling of the heavy particles in the bottom of said tank 6.

This apparatus has been used with a very high degree of satisfaction and has resulted in large savings of usable coal heretofore discarded and abandoned as waste. The apparatus may be operated at relatively low cost to increase largely the desirable mine output. It should be apparent that the form and arrangement of the apparatus may be varied widely within the scope of equivalent limits without departure from the nature and principle thereof.

I claim:

1. An apparatus for processing coal in a fluent sludge state comprising a centrifugal machine supported for rotation about a vertical axis, means for rotating said mechanism to separate the fluid and floatable solid impurities from the coal and discharging the coal substantially free from said fluid and impurities, means forming a conduit for conveying the fluent sludge to said machine, a valve for regulating intermittent passage of the fluent sludge through said conduit toward said machine, an agitator for agitating the fluent sludge at the influent side of said valve, and mechanism for operating said agitator continuously and also for operating said valve intermittently to cause intermittent passage of fluent sludge through said conduit during operation of said agitator.

2. An apparatus for processing and recovering usable coal from fluent sludge or slurry containing floatable solid impurities, comprising a centrifugal machine supported for rotation about a vertical axis for receiving and separating the fluid and floatable impurities from the usable coal and discharging the coal substantially free from said fluid and impurities, connections for rotating said machine, means forming a conduit for conveying the sludge or slurry to said machine, a valve for regulating the passage of sludge or slurry through said conduit toward said machine, an agitator at the influent side of said valve for agitating the fluent sludge or slurry and preventing settling of the floatable impurities, mechanism for continuously operating said agitator and also opening and closing said valve in-

termittently or leaving said valve unoperated during operation of said agitator as desired, and means for removing from said conduit quantities of the fluid and floatable impurities before said fluid and said impurities pass said valve.

3. An apparatus for processing and recovering usable coal from fluent sludge or slurry containing solid impurities, comprising a centrifugal machine supported for rotation about a vertical axis for separating the fluid and floatable impurities from the usable coal, walls forming a tank for receiving the fluent sludge or slurry containing the usable coal and the impurities to be separated therefrom, mechanism for delivering into said tank the sludge or slurry containing a mixture of bodies of usable coal of predetermined maximum size and impurities to be separated from the coal, means forming a conduit for conveying from said tank to said machine the sludge or slurry containing said impurities to be separated from the coal by said machine, a valve for regulating the passage of sludge or slurry from said tank through said conduit toward said machine, mechanism for

agitating the sludge or slurry in said tank and simultaneously opening and closing said valve intermittently, and a device for optionally controlling operation of said valve by said last named mechanism or leaving said last named mechanism free to operate while said valve remains unoperated, as desired.

4. An apparatus for processing and recovering usable coal from fluent sludge or slurry and floatable impurities, comprising a centrifugal machine supported for rotation about a vertical axis, connections for operating said machine, means forming a conduit conveying the fluent sludge to said machine, a valve regulating the passage of sludge or slurry through said conduit toward said machine, an agitator at the influent side of said valve for agitating the sludge or slurry, a pipe for discharging a stream of water into the sludge or slurry at the influent side of said valve, mechanism for continuously operating said agitator and intermittently opening said valve, and means controlling operation of said valve by said last named mechanism.
